UNITED STATES PATENT OFFICE

2,605,303

RATIO TYPE GALVANOMETER

Claude M. Hathaway, Littleton, Colo.

Application September 14, 1950, Serial No. 184,867

4 Claims. (Cl. 171—95)

1

The present invention relates to a galvanometer element, and more particularly to one which will deflect in proportion to the ratio of two currents.

In a number of instances where oscillographs are employed, as in the case of radio telemetering, it has been found desirable to provide an indication of the ratio of two currents. To conveniently provide such indication it would be desirable to have an oscillograph galvanometer which will deflect in proportion to the ratio of two currents.

Therefore, it is an object of the present invention to provide an improved ratio type galvanometer.

Still another object of the present invention is to provide a moving coil galvanometer element which will deflect in accordance with the ratio of two currents.

Other and further objects of the present invention subsequently will become apparent by reference to the following description taken in conjunction with the accompanying drawing, wherein:

Figure 1 is an enlarged plan view of a portion of a galvanometer element constructed in accordance with the present invention;

Figure 2 is a side view of the element shown in

Figure 1;

Figure 3 is a plan view of a galvanometer element and support therefor; and

Figure 4 is a side view of the device shown in Figure 3.

Referring to the drawing there is shown a galvanometer element having a coil 11, which is arranged at right angles to a second coil 12. The coil 12 is carried by two spools 13 and 14 placed inwardly a short distance from two similar spools 15 and 16, which support the coil 11. Mounted on the coil 11 is a reflecting mirror 17 which is secured thereto by suitable cement. One terminal of the coil 11 is connected to a wire 21 which engages a lug carried by the spool 15. The other terminal of the coil 11 is connected to a wire 19, which engages a lug carried by the spool 16. One terminal of the coil 12 is also connected to the wire 21. The other terminal of the coil 12 is wound in a helical manner to form a short coil 18 surrounding that portion of the wire 19, which is close to the spool 16.

A suitable support plate 22 is provided with a plurality of mounting holes 23. The plate 22 carries a post 24, which is insulated therefrom and which is connected to a binding post 25. Another post 26 is also insulated from the plate 22 and connected to another binding post 27.

2

One end of the wire 19 is connected to the post 24. One end of the coil 18 is connected to the post 26. The other wire 21 is connected to a support 28 carried by an adjusting mechanism 29 contained within a housing 31, which is provided with a removable cap 32 to give access to the adjusting mechanism.

For the sake of illustrating the construction certain exaggerations have been indulged in since in actual practice each coil is about $\frac{3}{16}$ inch wide and about $\frac{1}{2}$ inch long. In the manufacture of these elements the two windings 11 and 12 are each wound separately on their respective metal spools, and then the winding 12 is mounted with 10 in the winding 11 and cemented into position. The element and support therefor, shown in Figure 4, is then mounted on a suitable housing, which is carried by a permanent magnet, which provides a concentrated magnetic gap about .050 15 inch wide.

While for the purpose of describing the present invention a certain preferred construction has been illustrated in the drawing, it is to be understood that such variations are contemplated as 20 may be commensurate with the spirit and scope of the invention set forth in the accompanying claims.

I claim:

1. A galvanometer element mounted between 20 two supports comprising a pair of parallel spools having a winding thereon, said spools being connected to said supports by fine metallic ribbons, a second pair of parallel spools mounted at right angles to said first spools and having their ends 25 contacting said first winding, said latter spools having another winding thereon substantially filling the central space of said first winding, one terminal of which is connected to one of said ribbons, the other terminal being connected to a conductor wound for a short distance about the other ribbon.

2. A galvanometer element mounted between 30 two supports comprising a pair of parallel spools carrying a winding therebetween, said spools being connected to said supports by fine metal wires, said winding being conductively connected to said wires, a second pair of parallel spools having a winding therebetween and being mounted at right angles to said first winding, said 35 latter spools and winding being supported by and cemented to said first winding and substantially filling the central space thereof.

3. The combination comprising a support plate 40 having two supports insulated from each other, an insulated binding post, a pair of parallel spools

55

having a winding thereon, each spool having a support lug, a plurality of metallic ribbons interconnecting each lug with one of said supports; a second pair of parallel spools having a winding thereon, said latter spools and said winding filling the central space within said first winding and being cemented into position within said first winding with said latter spools at right angles to said first spools, said first winding being connected to said ribbons, said second winding being connected to one of said ribbons and to said insulated binding post. 10

4. The combination comprising a support plate having two supports insulated from each other, an insulated binding post, a pair of parallel spools having a winding thereon, each spool having a support lug, a plurality of metallic ribbons interconnecting each lug with one of said supports, a second pair of parallel spools having a winding thereon, said latter spools and said winding sub- 15

stantially filling the central space within said first winding and being cemented into position within said first winding with said latter spools at right angles to said first spools, said first winding being connected to said ribbons, said second winding being connected to one of said ribbons, and a connection from said binding post to said latter winding including a winding extending about one of said ribbons. 5
